UNITED STATES PATENT OFFICE.

CARL GEORG EMIL SALZBERGER, OF BURGSTEINFURT, GERMANY.

RING-SPINDLE BEARING.

SPECIFICATION forming part of Letters Patent No. 729,673, dated June 2, 1903.

Application filed March 20, 1902. Serial No. 99,044. (No model.)

To all whom it may concern:

Be it known that I, CARL GEORG EMIL SALZBERGER, a subject of the King of Saxony, residing at Burgsteinfurt, Westphalia, Germany, have invented certain new and useful Improvements in Bearings for Ring-Spindles, of which the following is a specification.

The present invention relates to ring-spindles in which through suitable channels fresh oil can be always applied to the bearings and the already used dirty oil without mixing with the fresh lubricating-oil is discharged into a hollow screw-plug, by which this dirty oil can be removed during the work.

I will describe this invention with reference to the accompanying drawings, in which—

Figure 1 shows a vertical section through the spindle-bearing; Figs. 2 and 3, a part vertical section and part cross-section of a non-adjustable ball-bearing, and Fig. 4 a series of ball-bearings arranged one above the other. Fig. 5 shows a modified construction with a spiral pipe; Fig. 6, a top view of the spiral pipe, and Fig. 7 a cross-section through the same.

The spindle *a* is mounted in the spindle-foot *b*, secured in the known manner to the ring-spindle frame.

The oil-chamber *c* is of a hollow conical form, the upper end being cylindrical. The upper cylindrical part serves as support to the upper part of the spindle-bearing *d*. This consists of two hollow cylinders of different diameters fitted together. The upper cylinder *d*, which is of greater diameter than the lower cylinder *d'*, fits accurately into the hollow cylinder of the spindle-foot *b*. The upper cylinder *d* of the spindle-bearing fits oil-tight on the conical surface *e* of the spindle-foot *b*. This oil-tight fitting can be effected in any suitable manner. In the upper part *d* of the spindle-bearing the hollow cylinder is enlarged and has its end formed with a fine screw-thread. The shoulder formed in the spindle-bearing *d* by the said enlargement is formed conical in such manner that the conical surface inclines outwardly. This conical surface serves as bearing *d²* for the balls *f*, the outer bearing being formed by a hollow cylinder *g*, introduced into the upper enlarged part and capable of shifting longitudinally. This part *g* has its lower end formed

with two conical surfaces, of which one lies in the opposite direction to the lower conical surface of the bearing, while the other surface can act upon the balls in such manner that on the downward shifting of the cylinder *g* it presses the balls against the spindle. The first-named coned surface, which has sharp inclination, prevents the falling out of the balls on the removal of the spindle, while the second conical surface, which is inclined to a less degree, effects the adjustment of the ball-bearing. The cylinder *g* is prevented from turning relatively to the bearing *d* by means of a pin *h*, passing through a slot in the latter. The adjustment and fixing of the cylinder *g* are effected by means of a screw *i*. A second step-bearing or ball-bearing *o* is also combined with the lower end of the spindle-bearing, such ball-bearing consisting of an annular groove *p'*, fitted with balls, and a bottom recess *o'*, also fitted with balls. The said annular recess *p'* is provided with a discharge-opening *p* for the lubricating-oil, and the bottom bearing *o'* is provided with a passage *q* for this purpose.

In order that fresh oil may always be supplied uninterruptedly from the oil-chamber *c* to the spindle-bearings, the spindle-bearing *d* is provided with holes *k*, made as large as possible, near the upper ball-bearing surface, either above or below the same.

In order to enable the dirty used oil formed by wear in the bearing *d²* to pass away without mixing with the fresh lubricating-oil, the upper cylinder *d* of the spindle-bearing is formed with a number of vertical channels *l*, running parallel with the spindle, so that the dirty oil is discharged at the lower part of the spindle-foot *b*. The lower part of the spindle-foot *b* is also formed as a hollow cylinder, provided at its open lower end with a screw-thread. For closing this open lower end there is provided a hollow screw-plug *m*, the cylindrical upward extension of which fits closely against a coned shoulder of the spindle-foot. All the separated oil now flows into the hollow screw-plug *m* and can be removed from this during the working; also, a supply of fresh oil can be introduced into the bearing during the working by means of an oil-spout *n*, communicating with the oil-chamber *c*.

Figs. 2 and 3 show an arrangement of the ball-bearing without adjustment. The balls cannot fall out of the annular channel in this arrangement, because the said channel is formed with a trapezoidal section. The balls project sufficiently through the open side of the channel to be maintained in contact with the spindle. The introduction of the balls is effected from above through one or more channels f' , the section of which corresponds exactly with the groove in which the balls run, the channel being also so formed that the balls cannot fall out of the same. The said channels for the introduction of the balls may be of any convenient number relatively to the size of the spindle-bearing, and they may either be vertical or be formed in a more or less helical direction.

Fig. 4 shows an arrangement of several ball-bearings for the spindle arranged one above the other instead of having only one, as at f , Fig. 1. The construction would otherwise be the same as described with reference to Fig. 1.

It is to be understood that although I have spoken of ball-bearings the balls may be replaced by small rollers or ellipsoidal bodies.

The ball-bearing being employed only with the view to obtain as large a free space as possible may also be replaced by a spiral pipe, which allows as well a large free space for the oil. This modification is shown in Figs. 5 and 7. Here a spiral pipe is placed

in the upper part of the spindle-foot instead of the balls. Notches r allow of the passage 35 of fresh oil through the hole k into the spindle. The bottom bearing may be arranged at convenience. The rest of the oil conveyance is quite similar to that of the first construction.

Having now particularly described the nature of my said invention, what I claim, and desire to secure by Letters Patent of the United States, is—

1. A spindle-bearing composed of a spindle, 45 a surrounding tube forming an intervening oil-passage, upper and lower bearing-surfaces in communication with said passage, a collecting-chamber, and means for separately conveying the waste lubricant from the upper 50 and lower bearing-surfaces to said chamber, substantially as specified.

2. A spindle-bearing composed of a spindle having an upper bearing and a lower bearing, means for conveying a lubricant to said bearings, a collecting-chamber, and separate means for conveying the waste lubricant from each of said bearings to said chamber, substantially as specified.

In witness whereof I have hereunto signed 60 my name in the presence of two subscribing witnesses.

CARL GEORG EMIL SALZBERGER.
